UNITED STATES PATENT OFFICE.

BERNARD D. WILLIS, OF CHICAGO, ILLINOIS, ASSIGNOR TO AUTOMATIC ELECTRIC COMPANY, OF CHICAGO, ILLINOIS, A CORPORATION OF ILLINOIS.

TELEPHONE-RECEIVER.

1,194,457.

Specification of Letters Patent. Patented Aug. 15, 1916.

Application filed August 25, 1913. Serial No. 786,588.

To all whom it may concern:

Be it known that I, BERNARD D. WILLIS, a citizen of the United States of America, and resident of Chicago, in the county of Cook 5 and State of Illinois, have invented certain new and useful Improvements in Telephone- Receivers, of which the following is a specification.

My invention relates to improvements in 10 telephone receivers, and particularly to that type of receiver in which the constant magnetism of the receiver is furnished by an electromagnet, no permanent magnets being employed in the receiver. Receivers of this 15 character are usually connected in series in the line, and the current for supplying the magnetism is furnished from the central office. The sensitiveness of a receiver varies with its inductance, which in turn depends 20 upon the strength of the energizing current. The most sensitive telephone receiver is one in which a given change of current (for example one milliampere) produces the greatest deflection in the diaphragm. This 25 deflection is proportional to the change in pull exerted by the electromagnet upon the diaphragm. The pull depends upon the strength of the magnetic flux produced by the current flowing through the coil. The 30 amount of magnetic flux produced by the current is not necessarily proportional to the current. The ratio of magnetic flux to current, first increases with increasing current arriving at a maximum and then decreasing 35 as the current becomes still greater. At the point of greatest ratio the given change in current (for example one milliampere) produces the greatest change in magnetic flux and hence the greatest change of pull on the 40 diaphragm. Therefore at this point the receiver is most sensitive.

Inductance and permeability are proportional to the ratio of magnetic flux to the current producing it. Hence inductance and 45 permeability arrive at a maximum simultaneously with the ratio of flux and current. Thus it is that the sensibility in a telephone receiver is marked by large inductance.

The object of my invention is, therefore, 50 to provide a receiver in which the maximum inductance is produced by the weakest current which is met with in practice—that is, the current which is received over the longest line by which the receiver will be used— 55 which inductance decreased with the in-

crease of the energizing current within the ordinary limits.

In the accompanying drawings I have illustrated one form of my invention.

In these drawings—Figure 1 is a longitudinal section of a telephone receiver embodying the principles of my invention. Fig. 2 is an end view of the same with the cap and diaphragm removed. Fig. 3 is an enlarged perspective view of the soft iron shell of the electromagnet. Fig. 4 is a detail view of the mounting or connection fitting by which the circuit conductors are connected with the coils of the receiver. Fig. 5 is a diagram of a telephone circuit, 70 illustrating the manner in which the receiver forming the subject matter of the herein disclosed invention may be connected to the line and supplied with energizing current from the central office battery. In Fig. 6 are 75 shown curves showing the relation of the magnetic and electrical properties of different receivers.

As illustrated in the drawings, it will be seen that my receiver comprises the usual shell C and cap D, which may be of any suitable form. In the lower or enlarged end of the shell C there is a non-magnetic cup A which is provided with a flanged edge a which is clamped between the shell C and the cap D, whereby the cup is held firmly in place. The electromagnet of the receiver comprises a coil of wire E wound upon a soft iron core e' and mounted 80 inside a soft iron cup or shell e. The electromagnet is secured to the bottom of the cup A by means of the screw e''. The diaphragm B is clamped in place between the cap D and the flange a of the cup A. To the back of the cup A there is secured a terminal block composed of insulating material and carrying the binding posts f'. The block is held in place by the screws f and f' which pass through the block and into the back of the cup. The binding posts 85 f' are provided with clamping screws f'' for holding the terminals of the receiver cord and with projecting portions f'' which extend through openings in the back of the cup A, where they may be connected to the 90 terminals of the coil.

The electromagnet which acts upon the diaphragm of a receiver should have a certain amount of constant magnetism in which fluctuations may be produced by the vary- 110

ing voice currents. The reason for this is that a feeble current will cause a greater magnetic disturbance in the field of a receiver if the core is magnetized than if it is not magnetized. The disturbance caused by a feeble current of a given strength increases with the strength of the field in the core up to a certain point—that is, the inductance of an electromagnet does not increase indefinitely with the increase of the magnetizing force, but rises to a maximum value and then slowly decreases. Therefore, in order to produce the most sensitive receiver of the kind shown herein, which is dependent for its constant energization upon the current which is supplied to the telephone over the line circuit from the central office battery, the electromagnet of the receiver should be so constructed and proportioned that the maximum inductance is attained by the current which is thus supplied to the telephone from the central office. Since in a telephone system all lines cannot be supplied with exactly the same amount of current on account of their unequal length and resistance, I have discovered that the most efficient results can be obtained by constructing the magnet to work above the knee of the B—H curve of the receiver, so that the maximum inductance will be produced by approximately the minimum current which the receiver will receive in practice. This is desirable for two reasons. First, the maximum inductance being produced by the minimum current used, rather than by the maximum current, the sensitiveness of the receiver will increase, instead of decrease, with the increase in the length of the line and consequent decrease of current. Second, there is a greater working margin as to the length of the line, since the slope of the curve above the knee is smaller than below and the range between the longest and the shortest lines is increased. The first feature, it is evident, is very desirable, because the longer the line the more feeble will be the voice currents received by the receiver.

In Fig. 6 I have shown a curve (curve No. 1), illustrating diagrammatically the relation of the current and inductance of a receiver constructed to give the results discussed above. By reference to this curve it will be seen that the maximum inductance occurs when the magnetizing current is at the minimum limit of the useful energizing current, approximately .044 amperes, and that this inductance gradually decreases as the energizing current increases from .044 amperes up to .10 amperes, which is approximately the maximum current which will be used in the usual telephone receiver. With this construction the sensitiveness of the receiver when the minimum current is employed is greatly increased. Thus the

operation of the receiver is rendered much more effective. In the curves 2, 3 and 4, which were plotted from ordinary receivers at present in commercial use, the inductance is much lower and increases continuously with the increase of current within the useful limits, so that the sensitiveness of these receivers, when used upon a long line, is less than when used upon a short line. Therefore their efficiency is greatly reduced. From this it will be seen that I have devised a very efficient form of receiver and one which gives highly efficient commercial results.

While I have illustrated in the drawings one particular form of receiver, it is, of course, to be understood that I am not limited to the exact construction shown.

What I claim as my invention is:—

1. In combination in a receiver, a coil, and a magnetic circuit including a receiver diaphragm associated with said coil, the said coil so wound and the magnetic circuit so proportioned that with an energizing current below the strength of one tenth (.10) ampere the inductance reaches a maximum.

2. In combination in a receiver, a coil, and a magnetic circuit including a receiver diaphragm associated with said coil, the said coil so wound and the magnetic circuit so proportioned that with an energizing current below the strength of one tenth (.10) ampere the inductance reaches a maximum, and with a stronger magnetizing current the inductance will be lower.

3. In combination in a receiver responsive to talking current, a diaphragm and an electromagnet, an electromagnetic circuit for said receiver including said diaphragm and the core of the electromagnet, which core and diaphragm are so constructed and proportioned and the coil so wound that the inductance of said receiver is greater with a current of one strength of flow than with a current of a greater strength of flow.

4. In combination in a receiver responsive to talking current, a diaphragm and an electromagnet, an electromagnetic circuit for said receiver including said diaphragm and the core of the electromagnet, which core and diaphragm are so constructed and proportioned and which coil so wound that the inductance of said receiver is greatest with a current strength below one tenth (.10) ampere.

5. In combination in a receiver responsive to talking current, a diaphragm and an electromagnet, an electromagnetic circuit for said receiver including said diaphragm and the core of the electromagnet, which core and diaphragm are so constructed and proportioned and which coil so wound that the inductance of said receiver is greatest with a current strength below one tenth (.10) ampere.

- ampere and less with a greater current flow.
6. In combination in a receiver responsive to talking current, an electromagnetic circuit, a coil, said coil associated with said electromagnetic circuit, said circuit so constructed and proportioned and said coil so wound that the inductance of said receiver is greatest with a current strength below one tenth (.10) ampere and less with a greater current flow. 45
7. In combination in a receiver, a coil, and a magnetic circuit including a receiver diaphragm associated with said coil, the said coil so wound and the magnetic circuit so proportioned that with an energizing current below the strength of one tenth (.10) ampere the permeability reaches a maximum. 50
8. In combination in a receiver, a coil and a magnetic circuit including a receiver diaphragm associated with said coil, the said coil so wound and the magnetic circuit so proportioned that with an energizing current below the strength of one tenth (.10) ampere the permeability reaches a maximum, and with a stronger magnetizing current the permeability will be lower. 55
9. In combination in a receiver responsive to talking current, a diaphragm and an electromagnet, an electromagnetic circuit for said receiver including said diaphragm and the core of the electromagnet, which core and diaphragm are so constructed and proportioned and which coil so wound that the permeability of said receiver is greatest with a current strength below one tenth (.10) ampere. 60
10. In combination in a receiver responsive to talking current, a diaphragm and an electromagnet, an electromagnetic circuit for said receiver including said diaphragm and the core of the electromagnet, which core and diaphragm are so constructed and proportioned and which coil so wound that the permeability of said receiver is greatest with a current strength below one tenth (.10) ampere. 65
11. In combination in a receiver responsive to talking current, an electromagnetic circuit, a coil, said coil associated with said electromagnetic circuit, said circuit so constructed and proportioned and said coil so wound that the permeability of said receiver is greatest with a current strength below one tenth (.10) ampere and less with a greater current flow. 70
12. In combination, a microphone transmitter and a receiver responsive to talking current passing through said transmitter, said receiver comprising a magnetic circuit including a diaphragm and an electromagnet coil, said coil being so wound and the magnetic circuit so proportioned that with an energizing current below the strength of said talking current the permeability reaches a maximum. 75
13. The combination of a circuit, of a microphone transmitter, a receiver and a source of energy for said transmitter, a current in said circuit controlled by said transmitter, said receiver comprising a magnetic circuit including a diaphragm and an electromagnet coil, said coil being so wound and the magnetic circuit so proportioned that as the energizing current decreases the permeability of the receiver increases. 80

Signed by me at Chicago, Cook county, Illinois, this 20th day of August, 1913.

BERNARD D. WILLIS.
